METHOD OF FORMING COMPOSITE
ARTICLES

Joseph E. Batie, Detroit, Mich., assignor to Kelsey-Hayes Wheel Company, Detroit, Mich., a corporation of Delaware

Application November 27, 1939, Serial No. 306,419

6 Claims. (Cl. 22—204)

The invention relates to the manufacture of composite articles and refers more particularly to the manufacture of composite brake drums.

The invention has for an object the economical manufacture of a composite article and more particularly a composite brake drum in a manner to secure the fusing of the materials together.

The invention has for other objects the heating of the annular flange of the shell of the composite article while it is substantially free of external heat conducting support to thereby greatly reduce the dissipation of the heat; the truing of the annular flange to correct any distortion thereof resulting from the heating prior to the casting of the liner in the annular flange; and the supporting of the annular flange externally during the casting to retain the shape of the annular flange.

The invention has for further objects the directing of the flame for heating the annular flange in a direction to reduce the harmful impingement of the flame upon the air excluding coating on the annular flange; the guiding of the flame to pass over the complete inner surface of the annular flange to completely heat the same; and to cast the liner material in a manner to avoid trapping of air.

These and other objects of the invention will become apparent from the following description, taken in connection with the accompanying drawings, in which

Figure 1 is an axial section through the brake drum shell;

Figures 2 and 3 are diagrammatic sectional views illustrating successive steps in the manufacture;

Figure 4 is a cross section on the line 4—4 of Figure 2;

Figures 5 and 6 are similar views showing other ways of carrying out certain of the steps;

Figures 7 and 8 are similar views also showing other ways of carrying out certain of the steps;

Figure 9 is an axial section through a completed brake drum.

The invention is particularly applicable to the manufacture of composite brake drums of the type illustrated in Figure 9. 1 is the wrought metal shell of the drum. The shell is preferably formed from sheet steel by a suitable drawing operation and has the annular flange 2 which is generally cylindrical and the web 3 which extends generally radially inwardly from an edge of the annular flange. The annular flange is formed with the generally cylindrical portion 4 connecting into the web and with the enlarged

generally cylindrical portion 5 connecting into the portion 4. 6 is a cast iron liner within and fused to the portions 4 and 5 of the annular flange and also to the peripheral part of the web. 5 The edge of the enlarged portion 5 extends beyond the free end of the liner and extends generally axially.

In the manufacture of the brake drum the wrought metal shell is preferably drawn from a flat sheet steel blank into the shape shown in Figure 1, in which it will be noted that the enlarged generally cylindrical portion 5 has at its free edge the flared portion 7.

After the shell of Figure 1 is formed, it is then 15 coated with a suitable flux, such as borax, boric acid, soda ash, or other salt having sufficient density to withstand the wash of the flame subsequently used in heating the annular flange of the shell. This coating is preferably accomplished by passing the shell through a flux bath. The coating serves to exclude air from the shell both before and during the subsequent heating and also to assist in fusing or molecularly bonding the cast iron liner to the shell during the 20 subsequent casting.

The coated shell is then placed in a suitable apparatus diagrammatically illustrated in Figures 2, 3 and 4 and axially moved outwardly to a position in which there is play or clearance between the flared portion 7 and the sealing element 8 of the apparatus by suitable means, such as the abutment 9 of the apparatus, which engages the central portion of the web. At this time the sealing element and the abutment and 25 also the shell are rotated in unison and during the rotation the annular flange of the shell is heated by means of the flame 10 which is produced by gas passing from a series of gas jets of the burner 11 which has been inserted inside the shell. The flame is directed in the general direction of rotation of the shell to reduce its harmful impingement upon the coating on the inner surface of the annular flange to thereby avoid destroying the coating. During the heating, the 30 sealing element and the web of the shell serve to retain the flame inside the shell and the sealing element also directs the flame so that it passes over the flared portion 7, the play or clearance between the flared portion and sealing element being sufficient for this purpose.

As a result, the flame comes in contact with the whole inner area of the annular flange thereby more uniformly heating the same. It will be noted that during the heating the flange is free from external heat conducting support so that heat dissipation is 35

reduced to the minimum. The heating is continued until the annular flange reaches a temperature of approximately 1300° F.

The sealing element 8 comprises the annular metal adaptor 8' and the metal sealing ring 8², the latter being coated with suitable heat resistant material, such as a material having a carbon base and a molasses binder. The material which I have found to be very satisfactory is formed by adding in a mixer while in operation the following ingredients in the following proportions: one quart of molasses to twenty-seven quarts of water, then fifty pounds of Face-A-Mould, which is gradually added, and finally slightly less than one quart of Hitempite solution, all being thoroughly mixed. The coated sealing ring is inserted into the adaptor ring before the flux coated shell is placed in the apparatus.

After the heating, the annular flange 2 of the shell is trued by correcting any distortion thereof caused by the heat. The truing also sizes the flange. This is accomplished by axially moving forwardly the external support 12 of the apparatus to externally engage the flange 2 in peripherally spaced zones and to also engage the flared portion 7 and to tightly clamp this flared portion against the sealing element 8. The external support rotates with the sealing element, the abutment 9, and the shell. The burner having been removed, the ladle 13 is immediately brought into operative position inside the shell, the parts at this time being in the positions diagrammatically illustrated in Figure 3. Each ladle is tilted to pour the predetermined quantity of the molten iron at a temperature in the neighborhood of 2700° F. to 3000° F. contained by the ladle against the inner surface of the annular flange of the shell, the rotation continuing until the molten iron has cooled sufficiently to solidify to allow the removal of the lined shell. The sealing element, in addition to preventing the flying out of the molten iron past the flared portion 7 of the shell, forms a dam preventing the molten iron from coming into contact with the flared portion. After the molten iron has been poured and has sufficiently solidified, the external support 12 is axially disengaged from the shell and the abutment 9 is axially drawn or forced back so that the lined shell may be withdrawn from the apparatus. The sealing ring 8² used in forming the lined shell is withdrawn with the lined shell and then separated therefrom.

For the purpose of preventing trapping of air in the enlarged generally cylindrical portion of the annular flange during the casting, the mouth of the ladle is shaped to pour the molten iron first into the enlarged generally cylindrical portion 5 and then into the generally cylindrical portion 4. As shown, the mouth of the ladle is formed with the notch 14 for this purpose.

The lined shell is next suitably operated upon to remove the inner face of the liner 6, thereby removing any impurities in the liner. Also the flared portion 7 is refashioned to extend axially. The final product is then as shown in Figure 9.

Figure 5 discloses another way of holding the brake drum shell during the internal heating of its annular flange. The shell in this instance, as shown, has at its free edge the radially extending annular flange 15 which is adapted to be held against the angularly spaced fingers 16 by means of the abutment 17 which engages the central portion of the web of the shell. There are preferably three equidistant fingers which are movable

10 with the support 18 and which in the retracted position of the support hold the brake drum shell spaced from the sealing element 19, which latter is stationary. With this arrangement it will be seen that the burner flame impinges completely over the inner surface of the annular flange of the shell and passes outwardly between its radial flange and the sealing element and passes over practically the complete outer face of the radial flange.

15 As illustrated in Figure 6, the annular flange of the shell is externally supported at peripherally spaced points by the support 18 which is advanced and this support, in addition, clamps the radial flange of the shell against the sealing element so that when the molten iron is poured against the inner face of the annular flange of the shell it cannot escape. The fingers 16 are advanced with the support and permit the radial flange of the shell to come into contact with the sealing element. To avoid detrimental chilling of the portion of the molten iron coming into contact with the sealing element, the metal sealing ring forming part of the sealing element is preferably provided with the filler ring 20 which is formed of suitable material.

20 As illustrated in Figure 7, the free edge portion of the shell during the internal heating of its annular flange is held spaced from the sealing element 21 by means of the angularly spaced fingers 22 which are engageable with the radially extending annular flange at the free edge of the shell. There are preferably three of these fingers and each is pivotally mounted at its middle and resiliently urged in a direction to engage the radial flange of the shell by suitable means, such as the coil spring 23, acting upon the tension member 24 which is connected to the end of the finger opposite that engaging the radial flange.

25 As illustrated in Figure 8, the annular flange of the shell is externally supported at peripherally spaced points by means of the support 24 which is adapted to be advanced after the heating operation and which clamps the radial flange of the shell against the sealing element, the fingers swinging under the resistance of their springs to permit the clamping.

30 The sealing rings of both sealing elements 19 and 21 are insertable into place so that they can be replaced after each casting step.

35 What I claim as my invention is:

1. The method of forming a lined brake drum, comprising providing a wrought metal shell having an annular flange with a generally cylindrical portion and a generally radial portion at one edge thereof, rotating said shell, and while rotating the shell carrying out the steps of heating the annular flange by passing a flame over substantially the entire inner surfaces of the generally cylindrical and radial portions, determining the size of and supporting the generally cylindrical portion and also clamping the generally radial portion against a sealing element by engaging an annular member with the outer surface of the generally cylindrical portion and with the generally radial portion, and pouring molten iron against the inner surface of the generally cylindrical portion while externally supporting the same and also while the sealing element protects the generally radial portion and forms a dam for retaining the molten iron.

60 2. The method of forming a lined brake drum, comprising providing a shell having an annular flange, rotating the shell in one direction with a protective coating on the inner side of the

flange, directing a flame on the inner surface of the flange in the general direction of rotation of the shell to thereby heat the flange, and pouring fluid liner material against the inner surface of the flange during the rotation of the shell.

3. The method of forming a lined brake drum, comprising providing a shell having an annular flange with two portions of different diameter, rotating the shell, heating the two portions during rotation, and pouring molten liner material against the inner surfaces of the two portions during rotation, initial pouring being against the inner surface of the portion of greater diameter only.

4. The method of forming a lined brake drum, comprising providing a shell having an annular flange with a generally radially extending portion at its free edge, rotating said shell, directing a flame on the inner surface of the flange during rotation of the shell, guiding the flame by a sealing element to pass over the generally radially extending portion, relatively moving the shell and sealing element to bring the generally radially extending portion into contact with the sealing element, and pouring molten metal against the inner surface of the flange during the rotation of the shell.

5. The method of forming a composite article comprising providing a shell having an annular portion, heating the annular portion, meanwhile rotating said shell and supporting the shell independently of the external surface of the annular portion, then pouring fluid liner material within and against the heated annular portion, and meanwhile rotating the shell and holding the heated annular portion from distortion.

10 6. The method of forming a composite article comprising providing a shell having an annular portion, rotating the shell and during the rotation directing a flame on the inner surface of the annular portion, meanwhile supporting the shell independently of the external surface of the annular portion thereof, then pouring fluid liner material within and against the heated annular portion, and meanwhile controlling the flow of the fluid liner material to retain the same within the heated annular portion with an end portion spaced from an end portion of the heated annular portion to form a groove, holding the annular portion from distortion, and rotating the shell.

JOSEPH E. BATIE.
